ELECTRICAL SWITCH ENCLOSURE

Lewis M. Lehman and John R. Stauder, Milwaukee, Wis.,
and David E. Scott, Royal Oak, Mich., assignors to
Square D Company, Park Ridge, Ill.

Filed Feb. 6, 1970, Ser. No. 21,318

Term of patent 14 years

Int. Cl. D13—03

U.S. Cl. D26—13

FIG. 1

FIG. 2

FIG. 3

FIG. 1 is a front perspective view of an electrical switch enclosure showing our new design.

FIG. 2 is an end elevational view; and

FIG. 3 is a side elevational view thereof, the side opposite thereto being substantially similar in appearance.

We claim:

The ornamental design for an electrical switch enclosure, substantially as shown and described.
